CORD SET FOR CHRISTMAS TREE LIGHTS

Curtis Barkes, Western Springs, Ill.

Application April 29, 1937, Serial No. 139,783

7 Claims. (Cl. 41—10)

The invention relates generally to the electric light cord sets, and more particularly to such cord sets made up of miniature sockets and especially intended and adapted for use in providing decorative illumination for Christmas trees.

Cord sets of this character ordinarily comprise a plurality of miniature sockets connected together in series by insulated electrical conductors, the end conductors or wires of a series of 10 eight or ten sockets being connected to a terminal plug connector of conventional construction.

In the use of such a cord set on a tree, the loop formed by the series of connected wires and sockets is usually placed around the tree and the 15 wires draped over and fastened to the tree branches so as to position the sockets and their associated lights in the most advantageous decorative relationship to the tree.

It is well known, however, that unless considerable care is taken in the placing of the sockets as well as in the placing and securing of the intermediate wires, these wires constitute a harsh or non-harmonizing factor in the desired decorative appearance of the tree, with the result that 25 there is required a considerable amount of later performed work and effort in concealing or rearranging the wires of the cord set. These changes or rearrangements often disrupt the decorative effect sought to be attained by the 30 relative positioning of the lights on the trees, and they constitute objectionable factors in the work of decorating a Christmas tree.

In view of these objections, an important object of the present invention is to provide a new and improved cord set of this character which is inherently decorative in all of its major parts, thereby enabling the user to dispose the lights about the tree in any desired position to insure the maximum decorative utility of the lights 40 themselves, and to employ such a disposal of the lights with assurance that the intermediate connecting wires will invariably enhance rather than detract from the decorative appearance of the tree as a whole.

More specifically, it is an object of the present invention to provide a cord set of this character wherein the wires intermediate the sockets have a decorative covering of tinsel or the like associated therewith in a relatively permanent manner, so that these intermediate wires constitute 50 truly decorative elements which harmonize with the usual or standard decorations applied to the tree.

Other objects and advantages will become ap-

parent from the following description, taken in connection with the accompanying drawing, in which:

Fig. 1 is a plan or side view of a cord set embodying the invention in its preferred form.

Fig. 2 is an enlarged fragmental view showing two of the light sockets of Fig. 1 and the intermediate connecting wire.

Fig. 3 is an enlarged sectional view taken along the line 3—3 of Fig. 2.

Fig. 4 is a view similar to Fig. 2 and illustrating an alternative embodiment of the invention; and

Fig. 5 is a sectional view taken along the line 5—5 of Fig. 4.

For purposes of disclosure, I have illustrated in the drawing and will hereinafter describe in detail the preferred embodiment of the invention, together with one alternative form thereof, with the understanding that I do not intend to limit my invention to the particular constructions and arrangements shown, it being contemplated that various changes may be made by those skilled in the art without departing from the spirit and scope of the appended claims.

In both of the alternatively usable forms chosen for illustration herein the invention is embodied in a cord set having a plurality of miniature sockets 10, each adapted to receive a conventional Christmas tree light or lamp 11, the sockets being electrically connected together by wires 12 so that the lamps 11 may be energized. The sockets 10 are of any preferred construction having an outer insulating shell with enclosed shell and center contacts (not shown) with which the electrical connections are made. In each instance two wires 12 extend into the socket 10, one wire being connected to the shell contact while the other wire is connected to the center contact.

While the series of sockets 10 included in the cord set may be connected in parallel, the present embodiments show series connections between the sockets, and the wires 12' from the two end sockets 10 are connected to the two terminals of a plug connector 13 which is used to connect the cord set to a source of current.

The wires 12 are, in each instance, of the insulated type, having a flexible rubber sheath 15 (Fig. 3) about the wire, and a protective fabric sheath 16 about the rubber or insulating sheath 15. These insulating and protective sheaths are, of course, left intact throughout all of the exposed portions between the sockets, and between the end sockets and the plug connector 13.

The length of the wires 12 between the several sockets is preferably such that a cord set having from eight to ten sockets comprises a relatively long string of connected light sockets which may be draped about a Christmas tree to produce an effective decorative arrangement and relationship of the lights. In this draping of the string of lights it is desirable that the user be able to give his entire attention to the disposal of the 10 lights or sockets themselves without regard to the arrangement of the intermediate wires 12, and in accordance with the present invention this desirable end is attained by providing a cord set wherein the intermediate wires have, in relatively 15 permanent association therewith, a decorative means which harmonizes with the customary tree decorations so that the wires, with their covering, constitute inherently harmonizing decorative elements for the tree. Preferably this decorative means is such that it may be produced and associated with the wires in a relatively 20 economical manner. With this purpose in view I have provided a concealing sheath 20 formed from tinsel and arranged to conceal the wires intermediate the sockets 10. The tinsel employed for this purpose comprises a plurality of fine metallic threads 21, which could, of course, be associated with or woven into the outer fabric sheath 16, but in the interest of economy and 25 convenience of manufacture I prefer to have the sparkling metallic elements 21 of the tinsel first associated with a central thread or cord 22 in the customary manner as indicated in Figs. 3 and 5, and thereafter to associate these strings 30 of tinsel with the wires of the cord set. This association may be accomplished in any preferred manner which produces a shielding of the wires from view by the casual observer; and as shown in Figs. 1 to 3, a plurality of strings (three in the 35 present case) of tinsel are wound in relatively high pitch spirals about the wires. The ends of the strings of tinsel are secured to the wire 12 adjacent to the plug connector 13 as by means of a bendable metallic clamp 25, and the spirals are 40 modified at each socket so as to leave the sockets exposed for the reception of the lights 11.

In the form shown in Figs. 4 and 5 of the drawing the decorative sheath is provided by arranging several, in this instance three, strings 50 of tinsel parallel to the wires 12 and in circumferentially spaced points about the wires 12, the strings of tinsel being held in substantially fixed relationship to the wires 12 by a series of metallic clamps 26 as shown in the drawing. The clamps 55 26, as well as the clamps 25, may be tightened in the degree necessary to hold the elements in the desired relationship.

If desired, each wire 12 may be concealed by a 60 separately formed sheath as indicated at the right hand socket of Fig. 4; or the strands of tinsel may be continuous from end to end of the string of sockets so as to continue past each socket as indicated at the left hand socket of Fig. 4.

From the foregoing description it will be evident that the present invention provides a cord set whereby a Christmas tree may be decorated more effectively and with less work than heretofore; and this result is attained by simple and 70 economically constructed means.

I claim as my invention:

1. A cord set of the character described comprising, in combination, a plurality of lamp sockets, a connector, wires electrically associated 75 with said connector and with said sockets to sup-

ply energizing current for lighting lamps placed in said sockets, said wires being arranged to provide an elongated string of sockets adapted to be draped about a Christmas tree with a substantial spacing of the sockets along the string, and a sheath of decorative tinsel fixed about said wires so as to substantially conceal said wires intermediate said sockets. 5

2. A decorative device of the character disclosed comprising, in combination, a plug connector, a plurality of lamp sockets, wires electrically connecting said sockets to each other and to said connector in spaced relation to energize electric lamps placed in said sockets, and a decorative sheath surrounding and substantially concealing said wires, said sheath being formed from strings of tinsel wound spirally about and fixed in position on said wires intermediate said sockets. 10

3. A Christmas tree cord set comprising, in combination, a plurality of lamp sockets, wires connecting said sockets electrically to each other, into an elongated string adapted to be supported about a tree, said sockets being spaced substantially from each other along the string thus formed, terminal means associated with said wires to connect said string to a source of current and thereby energize lights placed in said sockets, and decorative means permanently associated with said wires and operable to substantially conceal the same, said decorative means comprising a plurality of strings of tinsel extending longitudinally along said wires and disposed at circumferentially spaced points about the periphery of said wire, and means securing said tinsel strings to said wires at longitudinally spaced points along the wire. 25 30 35

4. In a device of the character described, the combination of a plurality of lamp sockets, wires electrically connecting said sockets in spaced relation to form a string of lights adapted to be draped about a Christmas tree, terminal means associated with said wires for connecting said string to a source of current so as to energize lamps placed in said sockets, said wires each comprising a flexible metallic electrical conductor and a flexible insulating sheath surrounding the conductor between said sockets, and a decorative concealing means formed from tinsel and permanently associated with said insulating sheath to conceal said insulating sheath from view. 40 45 50 55

5. A cord set for Christmas trees comprising, in combination, a plurality of lamp sockets, wires electrically connecting said sockets in spaced relation to form a string of light sockets adapted to be draped about a Christmas tree, terminal means associated with said wires for connecting said string to a source of energizing current, said wires each comprising a flexible metallic electrical conductor and a flexible insulating sheath surrounding the conductor between said sockets, and decorative means disposed along the wires intermediate said sockets in relatively permanent association therewith, said decorative means comprising a plurality of elements formed with an appearance harmonizing with standard 60 65 70 75 Christmas tree decorations.

6. In a device of the character described, the combination of a plurality of lamp sockets, wires electrically connecting said sockets in spaced relation to form a string of sockets adapted to be draped about a Christmas tree, said wires each comprising an electrical conductor and a flexible insulating sheath surrounding said conductor, and a decorative concealing means rela- 70 75

tively permanently associated with said wires between said sockets, said decorative concealing means comprising a plurality of shiny sparkling elements disposed along said wires.

5. 7. In a device of the character described, the combination of a plurality of lamp sockets, wires electrically connecting said sockets to form a string of sockets spaced substantially from each other and adapted to be draped about a Christ-

mas tree, each of said wires comprising a metallic flexible conductor and a flexible insulating sheath, and decorative means disposed along said wires outside of said insulating sheath, said decorative means comprising a plurality of shining surfaces arranged to substantially conceal said insulating sheath. 5

CURTIS BARKES.
